United States Patent Office

Des. 215,185
Patented Sept. 9, 1969

215,185

TOY MOVIE PROJECTOR

Karl A. Utrecht, Cincinnati, Ohio, assignor to Kenner Products Company, Cincinnati, Ohio, a corporation of Delaware

Filed Feb. 25, 1969, Ser. No. 15,910

Term of patent 14 years

Int. Cl. D16—04

U.S. Cl. D61—1

FIGURE 1 is a front perspective view of the toy movie projector from one side thereof;

FIGURE 2 is a rear perspective view from the other side thereof;

FIGURE 3 is a top perspective view from the one side thereof; and

FIGURE 4 is a bottom perspective view from the other side thereof.

I claim:

The ornamental design for a toy movie projector, substantially as shown.
